UNITED STATES PATENT OFFICE.

ADOLPH BINKERT, OF PHILADELPHIA, PENNSYLVANIA, ASSIGNOR TO CATERSON, BROTZ & CO., OF SAME PLACE.

DESIGN FOR THE ACE OF SPADES FOR PLAYING-CARDS.

SPECIFICATION forming part of Design No. 14,957, dated April 15, 1884.

Application filed March 13, 1884. Term of patent 3½ years.

To all whom it may concern:

Be it known that I, ADOLPH BINKERT, a citizen of the United States, and a resident of Philadelphia, Pennsylvania, have invented a new and Improved Design for the Ace of Spades for Playing-Cards, of which the following is a specification.

The nature of my invention is fully set forth in the accompanying illustration, to which reference is made.

What I claim as my invention is—
The design for the ace of spades for playing-cards, as shown.

ADOLPH BINKERT.
